UNITED STATES PATENT OFFICE.

JOHN W. POTTER, OF CRANSTON, RHODE ISLAND, ASSIGNOR TO ALBERT J. DRONSFIELD, OF PROVIDENCE, RHODE ISLAND.

SPRAYING-NOZZLE.

1,073,438.

Specification of Letters Patent. Patented Sept. 16, 1913.

Application filed February 19, 1913. Serial No. 749,560.

To all whom it may concern:

Be it known that I, JOHN W. POTTER, a citizen of the United States, residing at Cranston, in the county of Providence and 5 State of Rhode Island, have invented certain new and useful Improvements in Spraying-Nozzles, of which the following is a specification.

My invention relates to nozzles adapted 10 for use in humidifiers, oil burners and other such structures wherein a liquid is sought to be atomized by virtue of an induction by air or steam through the nozzle.

The objects of my invention are essentially to insure a more perfect atomization 15 than has heretofore been obtained; to procure this end without the presence of any drip at the nozzle; to increase the degree of atomization; and to attain these ends in a 20 simple and inexpensive manner.

A further object is to provide means for regulating the volume of water or air fed to the nozzle during its operation.

To the above ends my invention consists 25 in such parts and combination of parts as fall within the scope of the appended claims.

In the accompanying drawings which form a part of this specification, Figure 1 is a side elevation of a nozzle embodying my 30 invention, Fig. 2, a section of the same on line *xx* of Fig. 1, Fig. 3, an enlarged section of the portion of the nozzle head, and Fig. 4, a section on line *yy* of Fig. 2.

Like reference characters indicate like 35 parts throughout the views.

My nozzle in its present and preferred form of embodiment comprises a hollow cylindrical body 1 provided with a restricted or bearing portion 2 of less internal diameter 40 than the diameter of the remainder of the body, the interior of said body being provided with screw threads 4. The body is provided with an integral stem 5 provided with an axial passage 6 and external screw 45 threads 7. Fixed in the bearing 2 of the body as a forced fit is an intermediate portion of an arbor 8. An intermediate portion 9 of the arbor is in the bearing 2 and is provided with an annular shoulder 10 at one 50 end abutting against an internal shoulder 11 in the body 1. The portion of the arbor immediately in front of the shoulder 10 is of reduced diameter 12 and is provided near one end with a broad annular enlargement 55 13, provided with spirally disposed or in-

clined peripheral grooves or channels 14. Forward of the enlargement 13 the arbor 8 is tapering or inwardly inclined as at 15. The arbor is hollow throughout its length and has slidably mounted in its open central portion a liquid tube 16, whose forward portion 17 is contracted and terminates in a restricted central passage in its forward end 18. The axial opening of the arbor is somewhat enlarged at its forward portion forming an annular bevel 19, which combined with the tapering face 15 of the arbor forms an annular nose 20 V-shaped in cross section. The arbor 8 is provided in the rear of the portion 9 with external threads 22 upon which is mounted a knurled nut 24 provided with internal threads 25 engaging the threads 22 of the arbor, and provided with an inturned annular shoulder 26 upon its outer end. Soldered or otherwise fixed 60 to the liquid tube 16 is a bushing 27 provided at one end with an annular flange 28 abutting against the flange 26 within the nut 24. Fixed upon the bushing 27 adjacent the nut 24 is a second nut 30 provided 65 with external threads 31 engaging internal threads 32 upon a coupling nut 33 whose flange 34 engages the head 35 of the liquid pipe 36. The head 35 of the pipe 36 is curved and fits within a cavity in the end 70 of the nut 30. The supply pipe 36 leads from any convenient source of liquid supply. Mounted within the sleeve or body 1 around the forward portion of the arbor and spaced 75 from the latter is an adjacent sleeve 38 provided upon the exterior of its inner end with screw threads 39 engaging the threads 4 of the body, and provided at a short distance from its forward end with a conical shoulder 40 immediately forward of which the sleeve is provided with a nearly hemispherical annular cavity 41 forming at the forward extremity of the sleeve an inwardly directed curved flange 43 surrounding a restricted orifice 44 in front of the restricted portion 17 of the liquid pipe and the nose 20. It will be noted that the conical surface 15 of the nose and the surface of the shoulder 40 are spaced apart as best shown at 80 46 in Fig. 4.

The exterior of the sleeve 38 is provided with a knurled surface as at 48.

The operation of the nozzle is as follows: The liquid that is to form the material of the spray is drawn through the pipes 36 and 110

16 and out of the opening 18 at a point within the chamber 50 formed by the cavity 41 in the sleeve. This chamber 50 is an anti-expansion chamber. The liquid is induced 5 through the tubes 36 and 16 by the operating air or fluid passing under pressure through the opening 6 in the stem 5 of the body 1, which opening extends into the chamber or annular passage 51 within the 10 body 1 intermediate the shoulder 10 and the inner end of the sleeve 38, and passes thence through the annular space 53 between the sleeve 38 and the arbor, and thence through the grooves or channels 14 in the enlargement 13, and thence through the annular 15 converging opening 46 and thence into and through the antiexpansion chamber 50 in a manner to be forthwith described in more detail. The course of the air or fluid as it 20 emerges from the opening 46 is graphically indicated in Fig. 3 by the two sets of intersecting lines 55 and 56, whose points of intersection are located exterior of the end of the sleeve as at 57. The broken lines 55 25 and 56 indicate the conical character of the emerging air or fluid stream, which forms a resultant conical shaped vacuum area 58, which vacuum is the means of inducing the discharge of the liquid from the contracted 30 portion or nozzle 17 of the water pipe 16. Experiments have disclosed the fact that the greater the area of the vacuum the greater will be the force of liquid discharge, and the greater the resultant atomization of 35 the liquid. Experiment has further shown that a discharge of the air or fluid from the annular opening 46, unrestrained in any manner, results in an undue dispersion of the emerging fluid, in such a manner as to 40 prevent the formation of any substantial resultant vacuum. It was found however that the provision of an antiexpansion chamber 50 bounded by a contracted flanged portion 43 serves to house the adjacent air 45 and forms a back pressure exterior of the cone 55, 56 that overcomes the undue dispersion of the fluid forming the cone. The passage of the air through the grooves 14

causes a resultant rapidly rotating air cone, which at the points 57 of convergence pulverizes the liquid which issues in the form of fog. The volume of liquid is regulated by manually turning the knurled nut 24 upon the arbor 8. The volume of operating fluid is regulated by manually rotating the 55 knurled portion 48 of the sleeve 38, thereby controlling the extent of the opening 46. The enlargement of the opening 46 by moving the sleeve 38 and its shoulder 40 increases, by virtue of the increased volume of 60 fluid, the volume of liquid drawn through the tube 16. Longitudinal adjustment of the portion 17 of the tube 16 by the nut 24 insures the proper degree of pulverization under the changed conditions attendant 65 upon the change in the volume of fluid.

What I claim is:—

In a spraying nozzle, the combination with a hollow body, of a sleeve rotatably mounted in the body and provided with an antiexpansion chamber in one end, a hollow arbor fixed in the body and extending concentrically to the sleeve and spaced from the sleeve, an annular enlargement upon the arbor engaging the sleeve and provided with 70 inclined peripheral grooves, a liquid tube slidably mounted in the arbor and provided with a contracted end portion extending beyond the end of the arbor and concentric therewith, a nut upon the intermediate portion 75 of the arbor, a bushing fixed to the liquid tube provided with an annular shoulder engaging the nut, a second nut fixed to the bushing and provided with a cavity in one end, a liquid supply pipe, a curved head upon the liquid supply pipe 80 engaging in the cavity in the nut, and a coupling nut upon the last mentioned nut 85 engaging the head of the supply pipe.

In testimony whereof I have affixed my 90 signature in presence of two witnesses.

JOHN W. POTTER.
